(57) **CLAIM**

The ornamental design for a lampshade display, as shown and described.

DESCRIPTION

FIG. 1 is a front elevational view of a lampshade display according to my new design;

FIG. 2 is a top plan view thereof;

FIG. 3 is a right side elevational view thereof, the left side being a mirror image;

FIG. 4 is a rear elevational view thereof;

FIG. 5 is a bottom plan view thereof; and,

FIG. 6 is an enlarged sectional view taken on line 6—6 of FIG. 1.
